THERMAL SWITCH

Malcolm K. Parkhurst, New York, N. Y., assignor
to Control Products, Inc., Harrison, N. J., a cor-
poration of New Jersey

Application September 28, 1949, Serial No. 118,439

3 Claims. (Cl. 200—137)

1

This invention relates to thermal switches for electrical circuits, more particularly to thermal switches of small dimensions for use in high temperatures and especially adapted for use in fire-detection circuits.

The principal object of the invention is to provide such a switch which has no wearing surfaces which might throw the switch out of adjustment when it is subjected to long periods of sustained vibration as, for example, when used in the fire-detecting systems of airplanes.

Another object is to provide such a switch which is capable of being calibrated and thereafter hermetically sealed.

Another object is to provide a switch having terminal means subject to possible distortion when the switch is being connected in the circuit in which it is used, said terminal means being independent of the parts of the mechanism by which calibration is effected so that such stresses, or accidental stresses or strains, will not disturb the calibration.

Another object is to provide a switch having no spring contacts having initial bends creating stresses therein which may relieve themselves, thus destroying the calibration.

Other objects and advantages will in part appear, and in part will be obvious from the following detailed description of the present preferred embodiment of the invention, herein described for purposes of illustration, taken in connection with the drawings, in which,

Fig. 1 is a central sectional elevation through a complete switch which has been calibrated and sealed;

Fig. 2 is a plan view of the switch;

Fig. 3 is an elevation of the movable contact-carrying head attached to the rod taken on the line 3—3 of Fig. 1, and associated parts of the switch which are shown in central section, and

Fig. 4 is a plan view of the fixed contact member.

In describing the embodiment shown in the drawings, the construction of the completed switch will first be described followed by explanations of its mode of assembly and of its operation.

Structure

The switch embodies a rod and tube type thermal element in which the rod and tube have different thermal coefficients of expansion, the tube being attached to a housing carrying a fixed but resilient contact member suitably insulated from the grounded portion of the housing and electrically connected with another portion of

2

the housing serving as a terminal, the end of the rod being provided with a head which is slidable within the housing and carries the adjustable moving contact. As shown, the switch is designed to be normally open and to close upon the attainment of a predetermined elevated temperature.

Referring to the drawings, the switch comprises a tube 10 of suitable alloy such as "Inconel" and a rod 11 of a material having a lower coefficient of expansion, such as 42% nickel alloy. The specific materials of the tube and rod are, of course, subject to selection in accordance with the temperature ranges in which the switch is designed to operate, the selection being made in accordance with well understood principles. The lower or outer ends of the rod and tube are permanently and rigidly joined together in any suitable manner, preferably by means of the cup-shaped plug 12 which is spot welded to the tube 10 and to the center of which the rod 11 is riveted at 14. Preferably, the end of the unit is hermetically sealed by silver solder applied over the riveted end of the rod as shown at 15 and around the edge of the plug as shown at 16.

At its upper or inner end, the tube 10 is slipped over a cylindrical tubular boss 18, which forms part of the housing body 19 and is fastened thereon by spot welding. A mounting flange 20, which is provided with a central aperture to accommodate tube 10, underlies body 19 and is secured thereto by means of spot welding. Silver solder 21 hermetically seals the joint between the tube 10 and boss 18.

Body 19 provides a cylindrical chamber defined by its upstanding side wall which, prior to assembly, is not flanged over, as shown at 22, but stands straight up. Within this chamber is a mica washer 24 which rests on the bottom of the chamber and has an outer diameter corresponding to the diameter of the chamber. Resting on this washer is the fixed contact member shown in Fig. 4 which has a circular body 25 and a tongue portion 26, preferably provided with a separate contact element 28. This contact member is flat and the tongue 26 is resilient but sufficiently rigid to maintain its position under vibration. Being flat, this contact element contains no stresses, such as would be present if the contact were bent, so that calibration is maintained.

The second part of the housing is in the form of a hollow metal cap 29 in electrical contact with the fixed contact member through its outwardly extending flange 30, the outer diameter of which is somewhat less than the inner diameter

of the chamber in the body 19, so that it is spaced therefrom. Over flange 39 is a second mica washer 31 and a rigid metal washer 32 over which the flange 22 is turned to rigidly hold these parts together. The upper end of cap 29 is initially open and is counter-bored to provide a shoulder 34 surrounded by an initially cylindrical wall 35. Seated on the shoulder 34 is the annular flange 36 of a terminal plug 38 which is held in place by flanging over the wall 35, as shown at 39. The joint is then soldered at 40 to form an air tight seal. Plug 38 is internally bored and tapped, leaving its bottom closed, to receive the screw 41 under the head of which there is a washer 42. Instead of a female screw socket, the terminal plug may be provided with a threaded post.

At its inner or upper end the rod 11 is provided with a head 44 having a lower sleeve 45 closely fitting the rod and an upper internally threaded sleeve 46 which is preferably longitudinally split, as shown at 48 in Fig. 3, in which is inserted the contact-carrying screw 49 provided at its lower end with a suitable contact element 50. The sleeve 45 is fixed on rod 11 by welding. It is to be understood that the head may be integral with the rod, if desired. Sleeve 46 is split to provide tension on the screw 49 to hold it in its adjusted position. Screw 49 is located on a prolongation of the longitudinal axis of the rod 11 and its lower end, which carries the contact, extends into an aperture 51 which extends through the head 44 in a crosswise direction, at a right angle to the rod axis. The body of head 44 containing this aperture is so dimensioned as to have a sliding fit in the bore of boss 18. When finally assembled and adjusted, the contact elements 28 and 50 are spaced apart so as to provide a normally open switch.

The space existing between cap 29, the inner edges of washers 31 and 32 and of flange 22 of body 19 is filled with a fused glass seal 52 which may extend over the flange 22.

Assembly

The structure just described is assembled in the following manner: a sub-assembly is formed comprising the head 44 which is welded to one end of rod 11 and the plug 12 which is riveted to the other end of the rod. The second sub-assembly is formed by welding tube 10 to the boss 18 and by welding the mounting plate 20 to the underside of body 19, the common joint being filled with solder 21. The first sub-assembly is then inserted in the tube of the second sub-assembly, leaving the aperture 51 in the head 44 in a position above the top of the side wall of the body 19. The mica washer 24 is then dropped into the body, the tongue 26 of the fixed contact is inserted in the aperture 51 and the first sub-assembly is lowered into the body to its desired final location, which may be determined by means of a gauge designed to approximately center tongue 26 in the aperture 51. The two sub-assemblies are then connected by welding the plug 12 to the tube 10 and coating the joints with the solder shown at 15 and 16. The contact body 25 is centered in the housing body 19 by means of a jig and the contact may be temporarily held in place by a spot of adhesive. Cap 29 is then positioned over contact body 25, washers 31 and 32 are put in place and, while the cap is held in centered position, these parts are locked in body 19 by forming the flange 22 under very high pressure in a press. The glass seal 52 is then applied in the form of a slurry

which is baked and fired. The contact-carrying screw 49 is then inserted in the split neck 46 and adjusted to contact-closing position while the rod and tube are subjected to a fixed elevated temperature, the screw being adjusted to the position where the contact elements 28 and 50 are just brought into engagement. The position of screw 49 is then fixed by means of a seal 54 of chemically-setting heat-resisting cement. The terminal plug 38 is then placed in the open end of cap 29 and the flange 39 is formed and the joint is soldered at 40. The insertion of screw 41 completes the assembly.

As will be seen, the movable contact element 50 is connected to ground through the mounting flange 20 and fixed contact 26 is connected to the live circuit through cap 29 and the terminal plug 38 and screw 41.

Operation

When the tube 10 is subjected to high ambient temperature it expands, carrying with it rod 11 which has a lower coefficient of expansion. Head 44 moves with the inner end of the rod, sliding in boss 18 and moves the contact 50 toward contact 28. These contacts will close when the temperature is reached for which the switch is calibrated.

It will be observed that in the structure above described there are no points of possible wear which can affect the calibration of the switch, as in other structures where adjustment between two contacts is obtained, for example, by an adjusting screw the end of which bears against a contact or its carrier and in which the two surfaces may have relative movement when the device is subjected to vibration. The only relatively moving parts in the finally assembled device are the head 44 and the boss 18 but any wear taking place between these parts has no effect on the adjusted spacing of the contacts.

Furthermore, when a wire is connected to the device by means of screw 41, cap 29 may be subjected to stress. Even if this cap is moved or bent or distorted, it has no effect on the adjustment of the contacts because their spacing is independent of the position of the cap.

The final closure of the assembled switch by the terminal plug 38 permanently seals the switch against the possibility of tampering with the adjustment of screw 49.

While the invention has been described and illustrated by reference to one embodiment thereof, it is to be understood that it is not limited thereto since various details of construction may be changed without departing from the spirit of the invention. For example, the specific form of the aperture 51 in head 44 is capable of many modifications and the tube 10 might be secured to the inner surface of boss 18 instead of to its outer surface. Other possible modifications will readily be apparent to those skilled in the art and the invention is therefore to be construed broadly within the purview of the claims.

What is claimed is:

1. In a thermal switch, for use as a fire detector or the like, of the type having a rod and concentric tube of different thermal coefficients of expansion connected at their outer ends and having a two-part housing attached to the inner end of the tube, said housing comprising a body and a cap; a fixed electrical contact member rigidly supported in said body and insulated therefrom and having an integral resilient tongue portion extending over the end of said rod, the inner end

of said rod having a head provided with an aperture into which said tongue extends, said head having a threaded sleeve, a threaded electrical contact adjustably positioned in said sleeve and adapted to engage said tongue, said head being slidably supported in said housing, said cap being in electrical engagement with said fixed contact and having a bore in alignment with said sleeve through which said threaded electrical contact can initially be adjusted, and a terminal plug 10 forming a closure for said bore and hermetically sealed therein.

2. A normally open thermal switch adapted to close when subjected to excessive temperatures and capable of withstanding long periods of vibration in its normally open position without losing its calibration due to the absence of any wearing points therein affecting calibration, said switch comprising a rod and concentric tube of different thermal coefficients of expansion connected at their outer ends, a housing attached to the inner end of the tube and having a bore adjacent the tube the axis of which bore is aligned with the axis of the rod, a head carried by said rod slidably supported in and bearing against the wall of said bore, said head having a transverse opening communicating with a threaded opening which is on the opposite side of the head from said rod and aligned therewith, a fixed electrical contact member rigidly supported in said housing and having a stiff but resilient integral tongue portion extending into said transverse opening, an adjustable contact screw in said threaded opening adapted to make contact with said tongue portion at excessive temperatures, said housing having a passage through which said contact screw may be adjusted, and means for closing said passage after such adjustment.

3. A normally open thermal switch adapted to 40 close when subjected to excessive temperatures

and capable of withstanding long periods of vibration in its normally open position without losing its calibration due to the absence of any wearing points therein affecting calibration, said switch comprising a rod and concentric tube of different thermal coefficients of expansion connected at their outer ends, a housing attached to the inner end of the tube and having a bore adjacent the tube the axis of which bore is aligned with the axis of the rod, a head carried by said rod slidably supported in and bearing against the wall of said bore, said head having a transverse opening communicating with a threaded opening which is on the opposite side of the head from said rod and aligned therewith, a fixed electrical contact member rigidly supported in said housing and having a stiff but resilient integral tongue portion devoid of bends creating residual stresses therein and extending into said transverse opening, an adjustable contact screw in said threaded opening adapted to make contact with said tongue portion at excessive temperatures, said housing having a passage through which said contact screw may be adjusted, and means for closing said passage after such adjustment.
